(57) **CLAIM**

The ornamental design for a laboratory analysis device housing, as shown and described.

DESCRIPTION

FIG. 1 is a perspective view of a laboratory analysis device housing in accordance with the present teachings.

FIG. 2 is a front elevational view thereof.

FIG. 3 is a rear elevational view thereof.

FIG. 4 is a top plan view thereof;

FIG. 5 is a bottom plan view thereof;

FIG. 6 is a side elevational view thereof; and,

FIG. 7 is an opposing side elevational view thereof.

The broken lines immediately adjacent the shaded surfaces and the dash-dot-dash broken lines represent the bounds of the claim, and all other broken lines represent environment. None of the broken lines form part of the claimed design.
